UNITED STATES PATENT OFFICE.

LAWRENCE W. LUELLEN, OF NEW YORK, N. Y.

CUP-DISPENSING DEVICE.

1,043,854.

Specification of Letters Patent.

Patented Nov. 12, 1912.

Application filed June 19, 1909. Serial No. 503,068.

To all whom it may concern:

Be it known that I, LAWRENCE W. LUELLEN, a citizen of the United States, residing at New York, borough of Manhattan, in the county and State of New York, have invented a new and useful Cup-Dispensing Device, of which the following is a specification.

In certain places where water or other fluids are supplied as a beverage or for the purpose of rinsing the mouth, as, for example, in the offices of dentists, it is difficult even when the utmost care is exercised to keep a drinking vessel in common use in an aseptic condition. For this reason, it is desirable to supply each person with a clean individual cup, and under the conditions mentioned it is unnecessary to specially guard against waste or misuse.

20 The purpose of this invention is to provide a device of extreme simplicity for storing a supply of cups, in which they will be protected against the accumulation of dirt and contamination by handling and 25 which will always present a single cup ready for withdrawal.

In the accompanying drawings, Figure 1 is a full side elevation of one embodiment of my invention; Fig. 2 is a perspective view of the lower extremity of the cup-receiving tube; Fig. 3 is a central vertical section therethrough; and Figs. 4 and 5 are similar views of other forms of my invention.

35 Like numerals are applied to similar parts throughout the several figures of the drawings.

Upon a support or bracket 10, which may be arranged to stand upon or be secured to any convenient object, is mounted a tubular cup-receiver 11, preferably consisting of a metal or glass cylinder of considerable length and occupying a substantially vertical position. The cups C designed for use 45 with the device are of some thin, flexible material, such as paraffin or other waterproof paper, having their side walls tapering or flaring outwardly to the larger open end which is shown surrounded by a flange c. These are nested in a series one within another with the edges of the succeeding cups separated by narrow spaces, and are placed bottom down in the elongated chamber furnished by the opening through the 50 tube. This tube-opening is illustrated as cylindrical, and as its diameter is somewhat

greater than the maximum diameter of the cups at the flanges, the latter are capable of moving freely through it toward the delivery opening 12 at the lower extremity. 60

Above and immediately adjacent to the opening 12 is a reduced delivery passage 13 having preferably rigid walls fixed with relation to the receiver, the diameter of which passage is less than that of the cup flanges. 65 This passage may be cylindrical, and its length is such that when a cup is in engagement with the tube-wall near the upper portion of the passage the bottom of said cup will project from the device a sufficient distance to be readily grasped by the user. Between the chamber and delivery passage is a tapered throat 14, at least a portion of which is of sufficiently small diameter to frictionally engage the cup-flanges. 70 As particularly shown in Fig. 2 of the drawings, the walls of both the throat and delivery passage may be circumferentially discontinuous, the active surface being provided by separate ribs 15, or it may be continuous, as appears in Figs 4 and 5. In either case, the surface contacting with the ends of the cup flanges offers such frictional resistance that the weight of the entire stack is balanced when a few of said 85 flanges engage the throat and passage, but this should not be so great as to seriously impede the manual withdrawal of the terminal cup.

The operation of the device needs little 90 explanation. The nested cups are placed in the receiver-tube, as already described, with the lower one depending through the opening 12, and the top of the tube is closed by a cap or cover 16 to exclude dirt. When 95 one wishes to use a cup, the projecting end is grasped and drawn downwardly, the flexible flange and cup-walls yielding to permit such movement. This takes away some of the supporting resistance and the stack sinks 100 in the tube until equilibrium is restored. As the withdrawal continues and the weight of the stack diminishes, the terminal cup is positioned somewhat higher than at first, but the difference is too slight to materially 105 affect the operation, even in connection with the last of the series, which contacts with the tapered throat near the top but extends far enough below the tube to give a proper fingerhold.

110 The cylindrical passage is not essential to the satisfactory operation of the device, it

being rather in the nature of a guard to prevent the weight of the stack from accidentally forcing out one or more of the lower cups. It may therefore be entirely omitted, 5 or, as shown at 17 in Fig. 5, the tapered portion may be extended to the end of the tube, it being lengthened beyond what is actually necessary to support the stack. In this case it is, of course, essential that the 10 delivery opening be of such diameter that the resistance to the withdrawal of the cups is not excessive. It would preferably be somewhat greater than the diameter of the cups at the juncture of the tapered wall 15 with the flange *c*. It is obvious, however, that when cups without flanges are employed, the diameter of the delivery opening may be slightly less than the maximum diameter of the cups.

20 In the form shown in Figs. 2 and 3, wherein the cup-retaining surfaces are continuous, the cups are caused to buckle or flex in a definite manner by contact with the abutments as they pass along; that is, inwardly over the abutments and outwardly between them, thus tending to prevent any undesirable crack or fracture of the cup. In both of the illustrated forms of my invention it will also be seen that not only the 25 lowermost cup of the stack, but one or more of the cups immediately above it normally project through the cup-retaining means, thus insuring the proper guiding of the successive cups to the desired position and preventing them from becoming caught or held 30 in an inaccessible position.

It is obvious that many modifications and changes may be made in my invention from the forms specifically shown and described 40 herein and I do not mean to limit myself to these particular forms, but

What I claim and desire to secure by Letters Patent is:—

1. In a dispensing device, the combination 45 with a receiving chamber having a delivery opening and being normally closed except at said opening, of a stack of nested cups in said chamber and retaining means engaging a plurality of said cups and supporting the stack so that one or more cups project from said chamber so as to be grasped 50 for removal therefrom.

2. A dispensing device for nested paper cups comprising a receiving chamber hav-

ing a delivery opening and being normally closed except at said opening, means adjacent said opening and adapted to engage the lower cup of the stack for holding it normally in a position where it and the next succeeding cup of the stack project beyond the gripping means, thus insuring the successive guiding of all of the cups to operative position.

3. In a device for dispensing nested flexible cups, a receiving chamber for said cups having a delivery opening at the lower end thereof through which said cups are adapted successively to project, and gripping means arranged and proportioned so that the nest of cups is retained in the receiver 70 with the lowermost cup projecting therefrom through the delivery opening by means of the combined resistance to flexure of a plurality of said cups.

4. In a device for dispensing paper cups, 75 the combination with a holder for a stack of cups having a delivery opening, inwardly-projecting members adjacent said opening and adapted to engage a plurality of said cups while permitting a portion 80 thereof to project through said delivery opening.

5. A delivery device for nested paper cups comprising a vertically-arranged receiving chamber normally closed except for 85 a delivery opening at the lower end thereof, said chamber having an internal diameter greater than the maximum diameter of the cups, and a plurality of spaced cup-retaining abutments adapted to engage and flex 90 in a predetermined manner the bottom cups of the stack as they are withdrawn.

6. In a dispensing device for paper cups, the combination with a receiving chamber having a delivery opening and being normally closed except at said opening, of means adjacent said opening engaging and holding said cups so that the lower outer portion of the terminal cup is exposed for withdrawal bottom first, and its rim is with- 100 in the delivery opening.

Signed at New York, (borough of Manhattan), in the county and State of New York, this 15th day of June, 1909.

LAWRENCE W. LUELLEN.
